UNITED STATES PATENT OFFICE.

PHILIP F. WULLSCHLEGER, OF UNIVERSITY PLACE, NEBRASKA.

HEATING SYSTEM.

971,336.

Specification of Letters Patent. Patented Sept. 27, 1910.

Application filed October 25, 1909. Serial No. 524,432.

To all whom it may concern:

Be it known that I, PHILIP F. WULLSCHLEGER, a citizen of the United States, residing at University Place, in the county of Lancaster and State of Nebraska, have invented certain new and useful Improvements in Heating Systems, of which the following is a specification.

The present invention relates to heating systems and has for its purpose to provide an arrangement to be installed with furnaces whereby to overcome the heating of cellars, and wherein quicker and more effective results are obtained in heating the rooms.

The further purpose of my invention is to provide an apparatus of the type in question which may be readily installed with furnaces now in use at comparatively small expense, and which in its complete or original installation, *i. e.*, with the furnace, may be done equally as well as in the systems of heating now employed.

Another advantage embodied in my improved heating apparatus is that a large volume of air for heating may be accelerated in its circulation by a smaller draft of air, which is but an alternative arrangement when only a low fire is needed.

With the above purposes in view the invention is described in full in the following specification and the points of novelty thereof set forth in the appended claim.

The accompanying drawing shows the system in transverse sectional view.

Referring to the figure in more detail, the character A designates a furnace of the usual type and which may be of the hot air or hot water kind. The hood D thereof is provided with a funnel shaped double top as clearly shown. B are the outlet flues leading therefrom which distribute the heated air to the several rooms, and the number of these outlet flues may be increased or diminished all according to the extent of the building to be heated. The lower member C of the double top dome is at its center connected with a pipe E in precisely that manner shown. The flue E extends through the drum D and thence by an elbow is disposed downwardly to the floor G of the cellar or other basement. At just that point where the flue E reaches the floor of the cellar it

communicates with a main or underground chamber H which serves as the duct or inlet 55 for feeding the air to the flue E. Said chamber H is adapted to convey the cooler air from all of the rooms of the structure to be heated, and for the purpose is fitted with a flue J through which such air is directed. 60 The chamber H also communicates with the interior of the hood or drum D of the furnace as shown at the places indicated by a.

Within the pipe E, and preferably about midway of its length, there is a fan I which 65 is adapted to be driven by a motor I² or any other power, and has for its purpose to create the necessary flow of air through the pipes B, E, H and J.

After the heated air leaves the furnace 70 and supplies the rooms it is thence conveyed by the pipe J to the main H. From the pipe H part of this air enters the furnace drum through the underground passageways a, and the remainder passes through the flue 75 E into the chamber formed by the funnel shaped double top of the hood D and here it is thoroughly commingled with the usual heated air from the furnace issuing through the openings between the lower cover C and 80 the outlet pipes B, as will be clearly seen by reference to the figure.

There are several considerably important advantages resulting from the above described manner of heat and air circulation, 85 viz: the heated air is partially cooled by being conveyed through the flue J and by reason of this cooling, and the fact that it is thence conveyed by the underground pipe H to the flue E and openings a, said circulating 90 fluid acts as a means for cooling the cellar, and since the air of all the rooms is kept in constant circulation and the heat renewed in each circulation there naturally results a finer degree of heating in the rooms, and as 95 a consequence of this latter condition there is considerable economy from the fuel saving standpoint.

What I claim as new and desire to protect by Letters Patents is:

A heating system comprising a furnace having a hood provided with a double top of funnel shaped sections, said sections providing a chamber between them, outlet flues leading from said chamber and the space 105 beneath the lower of said funnel shaped

sections, a flue communicating with said chamber and extending to the outside of the hood, a flue located beneath the base of the furnace and communicating with said out-
wardly extended flue, and with the furnace hood at the base thereof; a third flue communicating with said underground flue, and a fan adapted to be driven by a motor for

accelerating the circulation of the air heated by the furnace. 10

In testimony whereof I affix my signature, in presence of two witnesses.

PHILIP F. WULLSCHLEGER.
